CLAIM

The ornamental design for a wing mirror, as shown and described.

DESCRIPTION

FIG. 1 is a left front perspective view of a vehicle wing mirror according to the present invention.

FIG. 2 is a right rear perspective view thereof.

FIG. 3 is a right front perspective view thereof.

FIG. 4 is a left rear perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof; and,

FIG. 10 is a left front perspective view of the wing mirror thereof, shown in a position of use.

The broken lines and the area between the broken lines illustrate environmental subject matter forming no part of the claimed design.

1 Claim, 10 Drawing Sheets
